(57) CLAIM

The ornamental design for the golf cleat, as shown and described.

DESCRIPTION

FIG. 1 is an elevational perspective view of the bottom of the golf cleat;

FIG. 2 is a top view of the cleat;

FIG. 3 is a side view of the cleat; and,
FIG. 4 is a bottom view of the cleat.

The broken line showing of the screw in FIGS. 2 and 3 is for illustrative purposes only and forms no part of the claimed design.
